(57) **CLAIM**

The new shape and ornamental design for the electric meter, as shown and described.

DESCRIPTION

FIG. 1 is a perspective view of the electric meter showing the new design;

FIG. 2 is a front view of the new design;

FIG. 3 is a rear view of the new design;

FIG. 4 is a left view of the new design;

FIG. 5 is a right view of the new design;

FIG. 6 is a top view of the new design; and

FIG. 7 is a bottom view of the new design.

FIG. 8 is a perspective view showing a status of the new design in use; and,

FIG. 9 is a perspective view showing another status of the new design in use.
